UNITED STATES PATENT OFFICE

ELLIOTT N. HALSTEAD, OF PRINCETON, WEST VIRGINIA

SPIT

Application filed April 4, 1929. Serial No. 352,470.

This invention relates to a spit for use by campers and others whereby bread, meats, vegetables, etc., can be held over a fire.

It is an object of the invention to provide a simple and compact device of this character which can be collapsed when not in use and carried conveniently in the pocket.

Another object is to provide a spit which, when collapsed, has its point completely housed so that it cannot cause injury.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings the preferred form of the invention has been shown.

In said drawings,

Figure 1 is a longitudinal section through the spit, the same being shown partly extended.

Figure 2 is a section through the collapsed spit with its housing cap in position.

Figure 3 is a section on line 3—3, Figure 2. Referring to the figures by characters of reference, 1 designates the outer tubular member or housing of the spit closed at one end by a cap 2 or the like from which a hook 3 or other attaching means is extended. The other end of the member 1 is exteriorly screw-threaded as at 4 for engagement by a housing cap 5. Said end of the member 1 is inturned to provide a retaining flange 4'.

Slidably mounted in the member 1 are telescopically connected tubular members 6, 7, and 8, each of which has an exterior flange 9 at one end and an interior flange 10 at its other end. The flange 9 of each member cooperates with the flange 10 or 4' of the next adjoining member to guide the member when

sliding and, if desired, a stop in the form of an intermediate flange 11 may be formed on each of the tubular members 6, 7, and 8 to limit the sliding movement of said members in one direction.

The innermost member 8 has a resilient stem 12 slidable therein, there being a collar 13 at the inner end of this stem while a barbed head 14 is at the outer end of the stem.

It is to be understood that any desired number of members 6, 7, and 8 can be employed, this depending on the size of the spit produced. Under normal conditions the spit is collapsed so that the several members lie within each other concentrically as shown in Figure 2. The barbed head of the stem 12 projects beyond the member 8. By screwing the cap 5 into engagement with the member 1 it will come against the end of the head 14 and hold said head and its stem 12 against longitudinal displacement. If desired, the cap 5 can be used as a means for thrusting against the head 14 and bowing the resilient stem so that the head will thus bite into the cap and hold it against rotation.

With the parts assembled as shown in Figure 2 the structure can be conveniently carried without danger of injury. When it is desired to use the spit the cap 5 is removed, the relatively movable parts are slid longitudinally to extend the spit, and the object to be cooked is then placed on the head 14.

What is claimed is:

1. A spit including telescopically connected members, cooperating means on the members for limiting their relative sliding movement, a pointed head upon one of the members, the said members being adapted to collapse for housing in one of the members, and a cap detachably engaging one of the members for holding all of the members collapsed and for engaging and housing the pointed head.

2. A spit comprising telescopically connected tubular members and a resilient mem-

ber having a pointed head, one of the tubular members constituting a housing for the other members, and a housing cap detachably engaging the housing member, said cap constituting means for engaging and housing the pointed head to bow the resilient member, said resilient member and its heads constituting means for retarding the rotation of the cap while in housing position.

10 In testimony that I claim the foregoing as my own, I have hereto affixed my signature.

ELLIOTT N. HALSTEAD.
